UNITED STATES PATENT OFFICE.

WILLIAM J. KEELEY, OF NEW YORK, N. Y., ASSIGNOR TO AUTO PNEUMATIC ACTION COMPANY, A CORPORATION OF NEW YORK.

AUTOMATIC GRAND PIANO.

1,184,537.

Specification of Letters Patent. Patented May 23, 1916.

Application filed October 11, 1911. Serial No. 654,105.

To all whom it may concern:

Be it known that I, WILLIAM J. KEELEY, a citizen of the United States, residing at New York, in the county of New York and State of New York, have invented a new and useful Automatic Grand Piano, of which the following is a specification.

The object of this invention is to provide a new and improved arrangement of parts in automatic grand pianos, particularly of that class which are arranged to be operated either manually or mechanically through pneumatic mechanisms.

To this end, the invention consists of the improved arrangement of parts herein shown and described.

Referring to the accompanying two sheets of drawings forming part of this application for patent, Figure 1 is a sectional elevation of the front part of a grand piano embodying my invention showing the piano closed but indicating in dotted lines the position of the parts when the piano is to be played manually. Fig. 2 is a partial view similar to Fig. 1 illustrating the position of the parts when the piano is to be played automatically. Fig. 3 is a front elevation indicating the position of the parts when the same are adjusted to the position shown in Fig. 2, and Fig. 4 illustrates a detail herein-after referred to.

Referring to the drawings and in detail, A designates the frame, B the key-board or piano front, these parts forming the piano casing C—C' the double fall board, D the keys, E the key bed, F the string frame, and G one of the action units of a grand piano having my improvements incorporated therein.

H designates the main lid and I the supplemental lid of the piano, the supplemental lid being hinged to the main lid and the main lid arranged to be raised in the ordinary manner common in grand pianos.

Ways 10—10 are formed in the piano frame and fitted to slide horizontally thereon is a shelf J pivoted or hinged to the front of which is the music desk K which has the usual foot L for supporting the music, foldably pivoted to the front end of the music desk K. The music desk is provided with one or more arms 11—11 pivoted to the back thereof and arranged to engage into notches 12 carried by the shelf J. By this arrangement, the shelf J and its parts can be slid

forward and backwardly horizontally in the piano casing and the music desk K and its foot can be turned to operative position, as indicated in dotted lines in Fig. 1, and the angle at which the desk is set can be adjusted by placing the arms 11—11 in different notches 12. It is understood, of course, that when the music desk is raised to operative position that the piano is opened either by turning the supplemental lid back on the main lid, or by turning the supplemental lid back on the main lid and raising both lids. When the piano is closed, the music desk is folded downwardly on the shelf, as indicated in full lines in Fig. 1.

The supplemental lid I is provided with a depending molding which conceals the front end of the shelf and music desk when the piano lids are closed.

The top of the key board B is formed in part of cross beam 14. Hinged to this cross beam is a base 15, which base normally hangs down in vertical position, as shown in Fig. 1, but which base can be swung to occupy a horizontal position, as shown in Fig. 2. One or more arms 16—16 is or are pivoted in the case at the rear of and near the bottom of the key board. Each of these arms has a slot 17, the upper end of which is enlarged so that a tongue 18 can project therein. The base 15 is provided on its sides with pins 19—19 which fit in the slots in said arms. By this arrangement, when the base is swung from vertical position shown in Fig. 1, to the horizontal position shown in Fig. 2, the same will be automatically locked in its horizontal position, and when it is desired to swing the same from horizontal position back to vertical position, the base is slightly lifted and the arms pulled forwardly to disengage the tongues 18 from the pins 19.

Secured to the base 15 are boards 20—20 and a board 21 is secured at the back of the boards 20—20. The boards 20—20 are arranged to carry the tracker and the note sheet operating mechanism. To this end, a tracker M is secured between said boards and said boards carry the usual bearings N—N for supporting the music roll. A music spool O is also mounted on bearings 105 carried by said boards 20—20 and the usual gearing for operating the music spool or the music roll is secured to the right-hand board 20, as shown in Fig. 3. A pneumatic motor P is arranged in the lower part of the piano 110

and particularly in a depending casing, as illustrated in my co-pending application filed of even date herewith, Serial No. 654,104. The driven shaft 22 of this motor carries a sprocket wheel 23 which is connected by a sprocket chain 24 to a sprocket wheel 25 arranged on a shaft 26 journaled in the piano casing at one side thereof. The shaft 26 is connected by a sprocket wheel 27, and a sprocket chain 28, to the sprocket wheel 29 of the gearing secured to the right-hand board 20. The shaft 26 is ranged substantially in line with the pivots or hinges of the base 15, and by this arrangement, as the base 15 is swung from vertical to horizontal, or from horizontal to vertical position, the connection of the gearing to the motor is not varied. The connection to the gearing to shift the gearing so as to actuate either the music spool or music roll is also arranged in line so as not to be disconnected by the swinging of the base 15.

If desired, an automatic tracking arrangement Q may be secured on top of the base 15 and connected to the right-hand bearing of the music roll. This automatic tracking mechanism may be operated through openings in the tracker and will serve to cause the music sheet to run in proper position laterally over the tracker. The automatic tracking arrangement and the gearing may be housed in by a suitable casing secured to the top of the base as indicated by dotted lines in Fig. 3, if desired.

A board 30 may be arranged between the board 20—20 so as to come over the tracker when the base 15 is swung to horizontal position, as shown in Fig. 2. The tracker has extending from the rear surface thereof, nipples connected to the perforations in the tracker and flexible tracker tubes 31 have their front ends placed on these nipples and their other ends placed on nipples extending out from a valve box R. This valve box is arranged in the position shown in Fig. 1, within the piano casing and in front of the action and over the keys. The valve box carries a set of primary valves S and secondary valves T which control a set of operating pneumatics U arranged at the rear of the valve box, and also in front of the action and over the keys. The pneumatics are preferably arranged in two banks and the pneumatics have pushers or abstracts 32 which are adjustably arranged to engage the actions, the pushers of the lower pneumatics passing through guides, as indicated in Fig. 4. The valve box is connected to a suitable vacuum-inducing apparatus.

The arrangements heretofore described are very desirable in that they do not detract from the appearance of the piano, and in that the pneumatics or apparatus is concealed when the piano is closed or played manually. When the piano is closed or

played manually, the base 15 occupies the position shown in Fig. 1. When the parts are in this position, the tracker and the music sheet manipulating mechanism are down in the piano case below the shelf and music desk and in front of the string frame and thus will be concealed from view as they come under the shelf J. When the piano is to be played mechanically or pneumatically, the supplemental lid I is folded back and both lids raised if desired, the shelf J and music desk pushed backwardly in the piano casing, and the base 15 swung up to horizontal position, as shown in Fig. 2. This will bring the tracker and music sheet manipulating mechanism completely above the piano casing and will bring the note sheet about to the position occupied by the music desk when the piano is played manually. This is a most advantageous position for the note sheet, as it comes to just about the place which the sheet of music occupies when placed on the music desk when the piano is operated manually and thus the operator can follow the note sheet just as easily as he reads a piece of music when playing the piano manually. The arrangement of pneumatics in front of the action and over the keys places them in position to operate most effectively.

The details and arrangements herein shown and described may be greatly varied by a skilled mechanic without departing from the scope of my invention as expressed in the claims.

Having thus fully described my invention, what I claim and desire to secure by Letters-Patent is:

1. An automatic grand piano having, in combination, a casing, a music desk mounted on said casing and movable into and out of operative position, a base hinged to the casing and movable to raised position when said desk is withdrawn from operative position, a tracker and sheet operating mechanism carried by said base, and means for supporting said base in raised position, said base when in lowered position supporting the tracker and sheet operating mechanism within the casing and below the desk and when in raised position supporting said parts so that the note sheet will substantially coincide with the position which the music desk occupies when in operative position.

2. An automatic grand piano, having in combination a casing, a shelf, slidably mounted therein, a music desk pivoted to the shelf, a base hinged to the casing below and adjacent to the shelf, and a tracker and sheet operating mechanism mounted on said base, the base being effective to support the tracker and sheet operating mechanism within the casing and below the music desk and also to support the tracker and sheet operating mechanism in operative position.

above the casing after the shelf and music desk have been pushed backward, said tracker and operating mechanism thereafter occupying substantially the position occupied by the music desk when in operative position.

3. In an automatic grand piano, the combination of the casing, a shelf slidably mounted thereon and carrying a music desk, a base hinged to the casing, a tracker and sheet operating mechanism mounted on the base, and means for holding the base so that

the tracker and sheet operating mechanism when in operative position will be substantially in the position occupied by the music desk when in operative position. 15

In testimony whereof I have hereunto set my hand, in the presence of two subscribing witnesses.

WILLIAM J. KEELEY
